UNITED STATES PATENT OFFICE.

JOHN A. LANNEERT, OF CLEVELAND, OHIO.

PRESS FOR FORMING TILE BLANKS.

Application filed October 3, 1925. Serial No. 60,186.

To all whom it may concern:

Be it known that I, JOHN A. LANNEERT, a citizen of the United States, and a resident of Cleveland, county of Cuyahoga, and State of Ohio, have invented a new and useful Improvement in Presses for Forming Tile Blanks, of which the following is a specification, the principle of the invention being herein explained and the best mode in which 5 I have contemplated applying that principle, so as to distinguish it from other inventions.

The present invention relates to machines for punching and cutting tile blocks. More 10 particularly the present mechanism is adapted for forming the end reinforcing tile plates such as are shown in my United States Letters Patent No. 1,365,705 dated Jan. 18, 1921. These end plates or blocks are used in 15 connection with hollow tile and are pre-formed and are then either hardened by burning as individual units and set up with the tile with mortar or cement or are air dried and then inserted in one end of the 20 tile and are baked or hardened therewith into an integral unit. In making such rectangular end plates, they are first extruded and cut to shape and the present machine is adapted to finish the block by punching 25 the centrally disposed aperture and at the same time notching the projecting ribs on both sides of the plate so that it may readily fit the building block. To the accomplishment of the foregoing and related ends, 30 said invention, then, consists of the means hereinafter fully described and particularly 35 pointed out in the claims.

The annexed drawings and the following description set forth in detail certain mechanism 40 embodying the invention, such dis- closed means constituting, however, but one of various mechanical forms in which the principle of the invention may be used.

In said annexed drawings:—

Fig. 1 is a front elevation of the machine; 45 Fig. 2 is a side elevation of the machine; Fig. 3 is a plan view; Fig. 4 is a horizontal section on the line 4—4 of Fig. 1; Fig. 5 is a perspective view of the extruded blank 50 before it is passed through the machine; Fig. 6 is a perspective view of the finished blank; Fig. 7 is a sectional view through a hollow tile with the blank mounted therein; Fig. 8 is a section similar to Fig. 7 but showing 55 the blank reversed and held in place by a mortar joint; Fig. 9 is a fragmentary sec-

tion showing a modified form of cutter in place; Fig. 10 is a front elevational view of the cutter shown in Fig. 9; and Fig. 11 is a sectional view through the cutter head shown 60 in Fig. 9 showing the relation of the cutter and wedge member.

The present invention comprises a base or table 1 having legs 2 and having an upright guideway 3 in which is slidably mounted a cross head 4. At the top of the guideway is mounted a drive shaft 5 having a driving pulley 6 and an eccentric 7 on which is mounted the connecting rod 8 which at its lower end is pivotally attached to the cross 65 head pin 9. The other end of the shaft extends beyond its bearing 80 and is provided with a pair of eccentrics 10. Attached to the cross head is the die or plunger 11, the table top being apertured as at 12 to allow 70 the plug cut from the blank to drop through the table. On each side of the table are a pair of bosses 13 in which are mounted rock 75 shafts 14 on which are rocker arms 15 connected to the eccentrics 10 by means of rods 16. Each shaft 14 is also provided with a crank 17 pivotally connected to a push rod 18.

Mounted longitudinally of the table top is a guide strip or track 20 which is provided at the front with an aperture 81 aligned with the aperture 12 in the table top. On each side of the table top are a pair of guide blocks 21 in which are slidably mounted cutter heads 22 transversely movable by 80 means of the push rods 18 to which they are pivotally connected. These heads are provided with a series of cutters 23 and 24, the cutters 23 at the ends of the heads being 85 formed of angles while the center cutter 24 on each head is of channel section. The cutters 23 at the top of the head are identical with the bottom cutters 23 except that they are reversed as to position so as to cut a corresponding notch on each side of the 90 blank. The center cutters 24 are also alike but the top cutter is open at the top and the lower cutter at the bottom. The guide strip or track 20 is notched to provide recesses 25 into which the cutters may pass. Mounted 100 over the cutters is a cover plate 26 which has two longitudinally extending ribs 27 forming an upper track and the plate has a slot 28 to allow downward movement of the 105 plunger or die.

The blanks 30 on which the machine is to operate are best shown in Figs. 5 and 6,

the blank as shown in Fig. 5 being rectangular in shape and being provided with a pair of ribs 31 and 32 on each face, the ribs 31 being spaced apart farther than the ribs 32 on the other face. These blanks are formed, preferably extruded on a separate machine and are then mounted on the track at the rear of the machine with the ribs 31 fitting the sides of the guide strip. A lever 35 is pivotally mounted on the table top and is provided with a roller 36 adapted to engage a blank so as to move it forwardly of the machine. An adjustable stop 37 is mounted on the table and so positioned that movement of the lever will force the forward one of two blanks in position under the plunger and opposite the transversely movable cutters. The next blank and movement of the lever will position the second blank and move the first blank out to the front of the table for removal. In its finished form the block is best shown in Fig. 6 with the ribs 31 and 32 cut away at the ends and with notches at the center. This allows the blanks to be inserted in the hollow tile either as shown in Fig. 7 where the ribs fit snugly into the tile for burning or hardening into an integral unit or as shown in Fig. 8 where the tile and block or plate are hardened separately and then secured together by mortar or cement filling 40. The blank is also preferably supplied with a groove or recess 41 for the insertion of a tool or wedge to pry the blocks apart after hardening.

In Figs. 9 and 10, a modified cutter arrangement is shown, the movable cutter head 69 having only two sets of cutters 70 and 71, the cutters 70 located centrally and the cutters 71 at the rear end of the head. Both sets of cutters are of channel shape and the cutters 71 are so placed that they overlap the two blanks and thus cut the rear notches in the front blank and the front notches in the rear blank at one stroke. The heads 69 are provided with slots 72 to receive the cutter blades, each cutter being made up of three adjustable cutter blades, 75 and 76, the bottom blade 75 fitting the bottom of the slot, while the two blades 76 stand vertically along the sides of the slot, being held in the desired spaced adjusted relation by a wedge block 77 which is mounted adjacent the top of the blades leaving an opening 78 for the cut portions of the ribs to pass through. A cover plate 73 is mounted over the blades and is secured to the head by means of screws and this plate is adapted to bear against the upper edges of the blades 76 to aid in holding them in position.

The operation of the machine is carried on in the usual way, the drive shafts being fitted with the usual type of clutch adapted to rotate the shaft one full revolution after the clutch is tripped. Such trip may be

.65 pedal or lever actuated or may be so placed

that the blank moving lever will trip the clutch as it moves to its final position against the stop. The blanks are thus punched and the ribs cut and slotted in one operation and the movement of the next blank into position to be operated upon forces the completed blank out on the table where it may be easily removed. The guide strips prevent the ribs from being bent or distorted during the cutting by the transverse cutters.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a machine of the character described, the combination of a table, a vertically movable die member, a track on said table for the blanks, two transversely movable cutter members, and driving means for simultaneously moving said die member to punch said blank, and said cutter members to notch said blank.

2. In a machine of the character described, the combination of a table, a vertical guideway mounted on said table, a die carrying a crosshead slidably mounted in said guideway, a track on said table for the blanks, two transversely movable cutter carrying heads mounted at the sides of said table, a drive shaft mounted in said guideway, and means connecting said shaft and said crosshead and said shaft and said cutters for simultaneously moving said crosshead and cutter heads to punch and slot said blank.

3. In a machine of the character described, the combination of a table, a vertical guideway mounted on said table, a die carrying crosshead slidably mounted in said guideway, a track on said table for the blanks, two transversely movable cutter carrying heads mounted at the sides of said table, a drive shaft mounted in said guideway, means connecting said shaft and said crosshead and said shaft and said cutters for simultaneously moving said crosshead and cutter heads to punch and slot said blank, and hand operated means for moving and positioning blank to be operated upon.

4. In a machine of the character described, the combination of a table, a vertical guideway mounted on said table, a die carrying crosshead slidably mounted in said guideway, a track on said table for ribbed blanks, said track forming a backing for the ribs, two transversely movable cutter carrying heads mounted on said table, a drive shaft mounted at the top of said guideway, and operating means connecting said drive shaft with said crosshead and with said cutter

heads for simultaneously moving said cross-head and cutter heads to punch said blank and notch said ribs.

5. In a machine of the character described, 55
 5 the combination of a table, a vertical guideway mounted on said table, a die carrying crosshead slidably mounted in said guideway, a track on said table for ribbed blanks, said track forming a backing for the ribs, 60
 10 two transversely movable cutter carrying heads mounted on said table, a drive shaft mounted at the top of said guideway, operating means connecting said drive shaft with said crosshead and with said cutter heads for 65
 15 simultaneously moving said crosshead and cutter heads to punch said blank and notch said ribs, and manually operated means for moving blanks into position for forming and for forcing formed blanks out onto 70
 20 said table for removal.

6. In a machine for forming tile blanks, the combination of a table, a vertical guideway mounted thereon, a crosshead slidably mounted in said guideway, a punch carried 75
 25 by said crosshead, a cutter head guide mounted on each side of said base, a transversely movable cutter carrying head mounted in each guide, a track mounted on said base to receive a ribbed blank, a cover 80
 30 mounted on said cutter head guides for forming a complementary track for said blanks, said two tracks forming backing for 85
 35 said ribs, means for moving said blanks along said track, and driving means mounted in said vertical guideway and connected to said crosshead and said cutter heads to simultaneously actuate the same to punch said blank and notch said ribs.

7. In a machine for forming tile blanks, 90
 40 the combination of a table, a vertical guideway mounted thereon, a crosshead slidably mounted in said guideway, a punch carried by said crosshead, a cutter head guide mounted on each side of said base, a 95
 45 transversely movable cutter carrying head mounted in each guide, a track mounted on said base to receive a ribbed blank, a cover mounted on said cutter head guides for forming a complementary track for said blanks, 100
 50 said two tracks forming backing for said ribs, means for moving said blanks along said track, a driving shaft mounted in said vertical guideway, connections between said shaft and said crosshead and cut- 105

ter heads to simultaneously move the same 55
 to punch said blank and notch said ribs, and means for moving said blanks to operating position and for forcing the finished blank out onto said table top.

8. In an adjustable cutter for tile forming machines, the combination of a cutter head having a slot, an adjustable blade mounted in the bottom of said slot, a blade vertically mounted at each side of said slot on said bottom blade, a wedge block adapted to be forced in said slot against said vertical blades to hold them into adjusted position, and a cover plate for said head adapted to bear on said vertical blades.

9. In an adjustable cutter for tile forming machines, the combination of a cutter head having a slot, an adjustable blade mounted in the bottom of said slot, a blade vertically mounted at each side of said slot on said bottom blade, and a cover plate for 75
 75 said head adapted to bear on said vertical blades to hold them in adjusted position.

10. In a machine for operating on plastic material, the combination of a table, a track on said table for the blanks, two horizontally movable cutter members mounted opposite each other adjacent said track, and driving means for simultaneously moving said cutter members transversely of said track and toward each other to notch said 85
 80 blank.

11. In a machine for operating on ribbed blanks of plastic material, the combination of a table, a raised track on said table for 90
 90 said ribbed blanks, two transversely movable cutters mounted opposite each other adjacent said track, and driving means for simultaneously moving said cutters to notch the ribs of said blank.

12. In a machine for operating on ribbed blanks of plastic material, the combination of a table, a raised track on said table for 95
 100 said ribbed blanks, the sides of said track acting as a backing for the ribs of said blank, an upper trackway forming a backing for the ribs on the upper surface of said blank, two transversely movable cutters mounted opposite each other adjacent said track, and driving means for simultaneously moving said cutters to notch the ribs of said blank.

Signed by me this 1st day of October, 1925.

JOHN A. LANNER.
